United States Patent Office

Des. 192,315
Patented Mar. 6, 1962

192,315

FOOT ORNAMENT

Wessie B. Moore, 4909 S. 29th Road, Alexandria, Va.

Filed Aug. 1, 1961, Ser. No. 66,161

Term of patent 14 years

(Cl. D7—7)

The FIGURE is a perspective view of a foot ornament showing my new design, the broken line showing of a foot being for purposes of illustration only.

I claim:

The ornamental design for a foot ornament, substantially as shown and described.
